UNITED STATES PATENT OFFICE.

AARON COLEMAN, OF NEW YORK, N. Y.

DESIGN FOR A SUSPENDER-BOX.

No. 38,057.

Specification for Design.

Patented June 5, 1906.

Application filed March 14, 1906. Serial No. 306,083. Term of patent 7 years.

To all whom it may concern:

Be it known that I, AARON COLEMAN, a citizen of the United States, residing at 45 East Seventy-sixth street, New York city, in the county of New York and State of New York, have invented a new, original, and ornamental Box for Suspenders, of which the following is a specification, reference being had to the accompanying drawing, forming part thereof.

The figure is a view in perspective of the suspender-box, showing part of the face and bust of a man on the cover of the same and an aperture in said cover.

I claim—

The ornamental design for a suspender-box as shown.

AARON COLEMAN.
